HELICOPTER TOY

Adolf Robins, White Plains, N. Y., assignor to
Tip Top Toy Company, New York, N. Y., a
copartnership

Application March 9, 1944, Serial No. 525,673

1 Claim. (Cl. 46—75)

The present invention is directed to toys, and more particularly, to a toy which has moving parts adapted to be actuated by the rolling thereof on wheels. Among such toys is a helicopter.

Toys of this type are well known, as, for example, there has been proposed a helicopter toy having a horizontal set of blades adapted to be rotated by the wind, and bevel gear connections between the landing wheels of the helicopter and the horizontal blades as well as the propeller thereof. These features rendered the toy quite expensive and the structure thereof was complicated. Therefore, it was easily broken or went out of commission with but slight handling.

The present invention is intended and adapted to provide a toy, for instance, of the helicopter type, which is simple in construction and which may be readily manufactured by relatively inexpensive workers.

It is also among the objects of the present invention to provide a toy wherein the motion of the driving wheels causes rotation of certain elements of the toy to simulate a natural action or movement.

In practicing the present invention, there is provided in a preferred form, a helicopter toy having a pair of driving wheels or landing gear and a horizontal helicopter propeller or set of blades. Extending downwardly from the blades is a rod in a vertical position and passing through an opening in the body of the toy. The opening is vertical and cylindrical and the diameter thereof is considerably greater than the diameter of the rod in order to allow a considerable space for lateral movement of the rod. At the lower end thereof is a horizontal friction disk adapted to cooperate with a friction wheel secured to the axle of the landing gear.

The helicopter blades extend laterally to points beyond the rim of the friction disk, and the weight of the rod and blades exerts a pressure between the friction disk and friction wheel, thus insuring adequate contact and a positive rotation of the blades upon rotation of the driving wheels. Even if the toy is not in a horizontal position, but is tilted to a considerable angle, the pressure exerted by the weight of the blades causes friction with said disk and wheel since there is no binding because of the large diameter of the opening through which the rod passes.

In the accompanying drawing constituting a part hereof, and in which like reference characters indicate like parts:

Fig. 1 is a side elevational view of a helicopter

toy made in accordance with the present invention, some parts being shown in cross-section for clearness; and

Fig. 2 is a front elevational view thereof.

The body or fuselage 1 of the helicopter toy has the usual vertical propeller 2 at the front thereof and the rear end 3 is provided with a tail 4 which consists of a vertically placed flat member secured by a groove and tongue arrangement 5 to the end 3. The lower end 6 thereof constitutes a tail skid and furnishes the third point of contact with the ground.

At the forward portion of body 1 there is a vertical cylindrical opening 7, and a rod 8 is fitted into said opening. The diameter of the rod is very substantially less than the diameter of the opening. To the top of the rod is secured a propeller hub 9 having a series of horizontal helicopter blades 10 radiating therefrom. The lower end of rod 8 is secured at the center of a friction disk 11 the rim 12 of which rests upon, and frictionally engages a vertically placed friction wheel 13. The latter is mounted on an axle 14, being fixed thereto, the ends of the axle having a pair of driving wheels 15 and 16 secured thereto. The extreme ends of blades 10 extend laterally to points beyond the rim 12 of disk 11 and assure a uniform pressure upon the disk in various positions of the toy.

A pair of flat pieces 17 and 18 are secured at 19 and 20, respectively, to the sides of body 1, at points approximately in line with opening 7. The lower ends are provided with openings 21 and 22, respectively, which act as bearings for axle 14 and allow free rotation thereof. A pair of substantially horizontal wings 23 and 24 are secured to the sides of body 1 at points just above pieces 17 and 18, respectively.

In the position shown in Fig. 1, the toy is at rest, with driving wheels 15 and 16 and tail skid 6 resting on a horizontal surface. In such position, rod 8 is approximately centered in opening 7. The weight of hub 9, blades 10, rod 8 and disk 11 is exerted upon friction wheel 13, forming a good frictional contact. When the toy is pulled, wheels 15 and 16 rotate causing rotation of axle 14 and friction wheel 13. The movement is transmitted to the rim 12 of disk 11 and this causes rotation of rod 8 and blades 10 mounted thereon. If the surface is not horizontal, rod 8 is not centrally located in opening 7, but is out of contact with the walls thereof, and thus the weight of the several parts is still exerted upon wheel 13, so that under all conditions of use the

helicopter blades will be revolved upon rotation of the driving wheels.

Although I have described the invention setting forth a single embodiment thereof, it is apparent that the principles set forth herein may be utilized in toys of similar nature but of different kind. For instance, one may make a toy cart having the mechanism described herein, and mount a human or animal figure on the rod 8 to give movement thereto upon the movement of the wheels of the cart. The top of the present invention is adapted to be made of wood and it can be readily and cheaply formed from this material. However, other materials of construction may be used, either in whole or in part. The exact arrangement, size and design of the several parts may be varied to a great extent, as will be quite apparent. These and other changes may be made in the details of the invention, which is to be broadly construed and not to be limited except by the character of the claim appended hereto.

What I claim is:

A toy helicopter comprising an elongated fuselage, a pair of driving wheels secured to an axle, said fuselage being mounted on said axle so as to allow rotation of said axle relative thereto, a friction wheel secured to said axle intermediate said wheels and parallel thereto, said friction

wheel being of lesser diameter than said driving wheels, a horizontal friction disk above said friction wheel and contacting therewith along its rim, a central cylindrical rod fixed to said disk and extending vertically upward through a vertical opening in said fuselage, said opening being cylindrical and its diameter being substantially greater than that of said rod, said rod and disk being free from direct connection with said body 10 and being adapted for lateral and vertical movement relative to said body, a set of helicopter blades mounted on the upper end of said rod and providing pressure on said friction wheel and disk, the outer edges of said blades extending 15 beyond the rim of said disk, wings extending laterally from the sides of said fuselage on opposite sides of said opening, said driving wheel mounting being secured to said fuselage below said wings, said wings being supported on said mounting, and a tail skid secured to the rear end of said fuselage, the height of said skid being such as to maintain said rod in vertical position when said toy is on an approximately horizontal surface, said skid being a vertically placed flat member joined to said fuselage by a tongue and groove arrangement and extending above said fuselage to simulate a tail.

ADOLF ROBINS.
